CASTING MACHINE

Squire D. Tyler, Vassar, Mich., assignor to Eaton Manufacturing Company, Cleveland, Ohio, a corporation of Ohio

Application June 3, 1952, Serial No. 291,410

4 Claims. (Cl. 22—90)

The present invention relates to a machine for the casting of molten metals and to suitable mold fixtures for use in connection therewith. More particularly this invention is concerned with the casting of molten metal in shell molds which are suitably supported by and positioned on multi-station rotatable turret type machines.

In the past, permanent mold casting machines embodying a plurality of cast iron molds carried by a rotatable turret-type frame structure have been used extensively in the casting of molten metals, particularly ferrous metals such as the casting of gray iron parts, etc. Cast iron permanent molds for such machines are customarily provided with the necessary cavities and projections to form the desired casting, and in use, the surface of the mold is first coated with a heat resistant adhesive of the general type disclosed in U. S. Patent 1,935,362, and second a parting layer such as graphite. After each casting is made in the mold, it is necessary to thoroughly clean the mold surface and to apply a new parting layer coating before again using the mold. One of the more important disadvantages of such permanent molds is that the castings which can be made therein are limited to relatively small sizes because of the problem of dissipating the heat from the molds. It is economically impractical in the quantity production of castings with this type of molds to make castings larger than about fourteen pounds in weight. Even when the casting size is maintained below this weight limit, the life of the molds is comparatively short.

The term "shell mold" as used in this specification and the appended claims is intended in its broad sense to include any relatively thin walled, self-supporting mold fabricated from conventional foundry sand and a resinous binder. It is commonly known that in order to cast molten metal in thin walled shell molds, that it is necessary to provide some type of exterior support for the molds. It has been suggested that loose shot or the like may be used to support the rear surfaces of the cope and drag or inner and outer sections of the mold. Such procedures are expensive and do not adapt themselves to quantity production or to the production of castings of large size.

It is, therefore, the principal object of this invention to provide an improved casting apparatus having provision for supporting shell molds thereon whereby the disadvantages of using permanent molds may be overcome and the casting of metallic parts in shell molds rendered feasible in production quantities.

Other objects of the invention include the provision of a casting apparatus which is improved by having a shell mold holding fixture and associated structure which insures adequate support for the shell molds and enables the manufacture of a variety of shapes of castings without limitation of the size thereof; the provision of an improved casting apparatus having shell mold supporting fixtures providing full support for the entire rear surface area of shell molds supported therein; the provision of an improved casting mold apparatus providing for the flow of cooling air over the surfaces of shell mold sup-

2

porting fixtures heated during the casting operation; the provision of a casting apparatus improved by provisions for automatically ejecting the casting from the shell mold and associated supporting fixtures.

5 Additional objects of the invention includes the provision of means for supporting one part of a multi-part shell mold supporting assembly so as to enable it to be advanced toward, or retracted from a cooperating portion; the provision of power means for moving one portion of a shell mold supporting assembly into and out of cooperative relation with respect to another portion thereof for supporting a shell mold between; and the provision of a shell mold supporting assembly including a pair of separable supporting fixtures and a cooperating track, one of the fixtures being wholly supported on the track and being movable thereon into and out of cooperative relation with the other of said portions by power means.

Further objects and advantageous features of the invention will be hereinafter specifically pointed out or 20 will become apparent upon considering the present disclosure in its entirety.

Casting machines of the present invention comprise a relatively large generally circular supporting frame structure or turret and suitable means for rotating the same 25 about its vertically disposed axis. A plurality of uniformly spaced shell mold supporting assemblies are provided adjacent the periphery and rotate with the turret. Each shell mold supporting assembly comprises a pair of supporting fixtures which cooperate with each other to support a shell mold therebetween. The shell mold supporting fixtures vary with the required amount of support of the shell mold as will hereinafter be more fully brought out. In a casting operation, the shell mold maintained between the supporting fixture halves substantially loses its identity as a unit due to the charring or conversion of the binder of the shell mold to a weak, crumbly state from the heat of the cast metal, and the mold may be easily separated from the resultant casting by simply shaking or jarring the casting. Each casting 30 requires a new shell mold, the shell molds being fabricated separately and inexpensively. Inasmuch as the molten metal contacts only the shell mold, the shell mold supporting assemblies have an extremely long life.

Each shell mold supporting assembly comprises a relatively stationary fixture with respect to the rotatable turret of an automatic casting machine of the type herein described, and a cooperating fixture movable with respect thereto, the two fixtures cooperating with one another to support a shell mold therebetween and to retain the same during a casting operation without crushing it. When such supporting assemblies are employed in conjunction with a casting machine of the type herein described, means are provided for maintaining the two fixtures in cooperating contacting relationship during a portion of each rotation of the turret. Means are additionally provided to separate the supporting fixtures during another portion of each complete rotation of the turret. Molten metal is poured into the shell mold maintained between the cooperating supporting fixtures during the portion of the rotation of the turret when the fixtures are maintained in contact with each other. The fixtures are separated from each other after the metal poured has solidified sufficiently to enable the ejection of the cast article, and the fixtures are maintained in separated relation until a point in the rotation of the turret immediately preceding the point at which the metal is poured. Power means are provided for automatically advancing and retracting the movable half of each shell mold supporting fixture 50 towards and from its cooperating fixture. Modified forms of supporting fixture construction are provided to enable the casting of intermediate weight and extremely

large castings, these modifications providing intermediate proportions of shell mold support or complete support of the rear surfaces of the shell molds. As the proportion of the rear surface of the shell mold which is supported by actual contact with metallic portions of the supporting fixtures is increased, the heat transmitted through the mold to the fixtures likewise increases. While the quantity of heat transmitted through the shell mold wall to the fixture is in all cases much less than is absorbed by permanent molds, for extremely large castings it is preferred and means have been provided for cooling the shell supporting fixtures. The supporting fixtures are each so constructed that air may be caused to continually flow over the rear faces of the supporting fixtures and cooperating means is provided to maintain a flow of air thereacross.

In the drawings:

Figure 1 is a fragmentary top plan view of a casting machine embodying the present invention;

Figure 2 is a fragmentary vertical sectional view taken axially through the casting machine illustrated in Fig. 1;

Fig. 3 is an enlarged horizontal view through one of the shell mold supporting assemblies taken along the line 3—3 of Fig. 2;

Fig. 4 is a vertical sectional view illustrating the disposition of shell mold supporting and retaining means taken along the line 4—4 of Fig. 2;

Fig. 5 is a vertical sectional view taken on the line 5—5 of Fig. 2 showing the disposition of supporting and yieldable retaining means;

Fig. 6 is a vertical sectional view taken along the line 6—6 of Fig. 3 and looking in the direction of the arrows;

Fig. 10 is an enlarged horizontal sectional view of a shell mold supporting assembly of the type illustrated in Fig. 8 and showing a modification thereof; and

Fig. 11 is a vertical sectional view taken along the line 11—11 of Fig. 10.

Referring to the drawings in greater detail, it may be seen in Figures 1 and 2 that there is provided a casting machine which includes a suitably fixed supporting base or structure indicated generally at 15 which base is provided with a fixed vertically extending cylindrical post 17. Rotatably mounted upon the post 17 is a drum-like member 19 which forms the central member of the rotatable turret. Member 19 is provided with a suitably bushed central hub 21 which rotatably receives the post 17 for guiding the drum member 19 in its rotating movement. The thrust of the turret is absorbed by suitable thrust bearing elements 23 disposed between the drum member 19 and the supporting base 15.

A plurality of radially extending equally angularly shaped supporting arms 25 are rigidly secured to the peripheral surface of the drum 19 and project radially outwardly therefrom; the outer ends of the arms 25 are connected by cord members 27 and the cord members 27 together with the arms 25 form a generally circular radially spoked frame structure. The arms 25 are hollow and the hollow interiors are in open communication with the interior of the drum member 19. The upper end of the drum member 19 has suitably secured to its upper edge an annular plate-like member 29 which extends radially inwardly from the outer edge thereof. Plate member 29 has secured thereto adjacent its inner edge, an upwardly extending circular housing 31 and forms the sole support therefor. Circular housing 31 is provided with an annular cored passage 33 therein which serves as a distributing 75

duct for compressed air which is used to actuate the movable portion of the shell supporting assembly.

The upper end of the hub 21 of the drum-like member 19 is closed by a cap member 35, the interior of which is divided into completely separated upper and lower chambers by means of a crosswall 37. The interior of the duct 33 in the member 31 is connected by means of a pipe 42 with the interior of the upper chamber in the cap 35. The interior of cap 35 additionally communicates with a suitable source of compressed air or suitable motive fluid by means of a tube 43, elbow 45 and upwardly extending pipe 47.

Spider 49 is suitably rotatably supported upon the upper end of the cap 35 and terminates at its periphery in a ring 51, the lower edge of which is so constructed and arranged as to cooperate with the upper edge of the housing member 31 so as to minimize the leakage of air therebetween. A stack or flue 53 is attached to the upper edge of the ring 51 and serves as the flue through which air employed in the cooling of the mold is withdrawn. Vertically disposed stack 53, spider 49 and ring 51 remain stationary during the rotation of the turret.

In order to secure the rotation of the turret, the lower face of drum member 19 has an internal gear 55 concentrically secured thereto. A transmission mechanism including a casing 57 rigidly fixed with respect to the base 15 and a spur gear 59 lying in mesh with the gear 55 is employed for rotating the turret. The gear 59 is fixed upon a vertical shaft 61 rotatably mounted in the casing 57 and within which has fixed thereto a ring gear 63. The ring gear 63 meshes with a pinion 65 fixed upon the rigidly extending shaft 67 which is rotatably mounted within the casing 57 and one end of which projects therefrom and receives thereon a coupling member 69. The coupling member 69 is employed for connecting the shaft 67 to one element of a variable speed device of known construction including elements 71 and 72, which are connected together and adapted to be driven by the electrical motor 75 of the synchronous or constant speed type. The motor 75 and speed reducing units 71, 72 are fixed in suitable aligned relation upon a common base 77. It will be appreciated that the speed of rotation of the turret may be controlled as desired by conventional adjusting means provided in connection with the speed reducing units 71, 72 and that the turret is preferably rotated at a speed as fast as will produce the desired quality of cast article.

The turret is provided with a plurality of identical shell mold supporting assemblies, each assembly being supported between the outer ends of each adjacent pair of arms 25. Each shell mold supporting assembly includes a fixture stationary with respect to the turrets and an opposed fixture movable relative to the turrets. Each fixture includes an inner plate-like member and a support. As shown in Fig. 2, inner plate-like member 79 is secured by means of bolts 83 to a vertically extending support 85 and together constitute the stationary fixture generally designated 90. Similarly, inner plate-like member 81 is secured by means of bolts 83 to vertically extending support 89 and together constitute the movable fixture generally designated 92.

The support 89 is fixed as by bolts 91 to the upwardly extending flange 93 of a carriage including a pair of spaced parallel arms 95 arranged in generally radial relation with respect to the axis of rotation of the turret and the outer and inner ends of which each rotatably support a grooved roller 97. The groove rollers 97 at each side of the carriage 95 are received upon corresponding rails 99. The rails 99 are supported from the arms 25 by means of a plurality of cross-bars 101 extends between and fixed to the lower faces of the cooperating pair of arms 25.

As may best be seen in Figs. 4 and 5, inner plate-like members 79, 81 are provided with a plurality of inwardly projecting pins, the function of which is to support and

maintain a shell mold generally designated 84 between the fixtures 90 and 92. As shown, shell mold 84 is comprised of cope and drag or outer and inner sections 86, 88, the inner surfaces thereof defining a mold cavity 82. Member 81 which moves toward and away from member 79 is provided with a plurality of dowel pins 103 fixed therein, which are adapted to cooperate with and to be slidably received by correspondingly positioned apertures 104 in inner plate-like member 79. Dowels 103 and apertures 104 insure the accurate alignment of the fixtures 90, 92 during the final stages of the closing movement. Stationary member 79 is provided with a plurality of semi-cylindrical pins 106, the flat surfaces of which conform to the outline of a shell mold 84 supported thereon. Pins 106 enable the rapid and accurate positioning of shell mold 84 on the stationary plate-like member 79 by the operator during that portion of the rotation cycle of the turret when the fixtures are separated. As will be noted, the remaining pins in stationary and movable members 79, 81 are positioned in corresponding locations and occur in opposed pairs, the pins in stationary plate 79 bearing correspondingly primed numbers to designate the correspondence. Pins 108, 110, 112, 114, 116, 118, 120, 122 and the opposed primed numbered pins on plate 79 are yieldably supported and are slidably received by corresponding apertures in the plates 81 and 79 respectively. As best seen in Fig. 6, the yieldable loading of the pins is accomplished by providing the outer ends of pins 122, 122' with enlarged diameter shoulder portions 122a and 122a' and outwardly projecting stub sections 122b and 122b' adapted to accommodate springs 124, 124' which are positioned therearound. The outer ends of springs 124, 124' encircle and are supported by inwardly extending stubs 125, 125' and rest against stud collar portions 123, 123'. The outer ends of studs 125, 125' are anchored in corresponding apertures in vertically disposed plates 126 and 126' respectively. It will be apparent that pins 122, 122' may move through inner plate-like members 81 and 79 against the tensions of springs 124 and 124', and will be maintained by springs 124, 124' in "at rest" positions wherein shoulders 122a and 122a' are positioned in blind recesses 121 and 121' in members 81 and 79 respectively. Plates 126, 126' are clamped between the flat face of each support 85 or 89 and the cooperating inner plates 79 or 81 by bolts 83. The inner ends of pins 108, 110, 112, 114, 116, 118, 120, 122 are in direct abutment with the rear surfaces of the cope and drag sections 86, 88 of the shell mold 84 and yieldably maintain the same in position without crushing or otherwise marring or deflecting the inner surfaces thereof. It is to be understood that the number of yieldable pins and their location may vary with the location of the recesses and projections in the shell mold surfaces as well as the relative size of the object to be cast. In general, the number of pins is preferably increased with increasing size of the casting and the location of the pins is preferably at points which are remote from the recesses or projections on the surface of the shell mold which is to be contacted by the pin ends. The positioning of pins at points immediately adjacent to points of change of contour of the shell mold tends to accelerate mold breakdown where the pin ends do not conform to the mold contours and should be avoided.

For the casting of somewhat larger objects of intermediate size such as objects weighing about fifteen to twenty-five pounds, it is usually desirable to provide reinforcement for a greater proportion of the area of the shell mold than is provided by the spaced cylindrical pins as described above. Fig. 9 illustrates a modified embodiment suitable for the accomplishment of this objective. As there shown, a single cavity mold 140 having a relatively large cavity 142 and thin shell inner and outer sections 141, 143 which are positioned in abutment with semi-cylindrical pins 144, 145 carried by and rigidly secured to stationary inner plate-like member 146. Shell mold 140 is partially retained in position by opposed pairs of

spring loaded pins 148, 148' and 150, 150' positioned adjacent the side extremities of the mold. The central portion of mold 140 surrounding cavity 142 is reinforced by two sets of pin members 152, 152' and 154, 154'. The inner ends of pins 152, 152' and 154, 154' are provided with extensions 153, 153' and 155, 155' respectively, which are shaped or contoured to conform to a portion of the shape of the projections on the rear surfaces of the mold 140. As explained above in connection with the 10 spring loaded pins of Fig. 6, the pins 148, 150, 152, 154 and the opposing prime numbered pins likewise act against the tension of suitable springs positioned on their outer extremities and abutting against rigid plates 156, 158.

In the casting of extremely large objects or of objects 15 having localized weight concentration so that adequate support may not be accomplished conveniently by either of the foregoing described supporting assemblies, the assembly illustrated in Fig. 8 may be advantageously used. As there illustrated, the shell mold supporting assembly 20 comprises a pair of fixtures generally designated 210 and 212. Fixtures 210 and 212 are provided with inner plate-like members 211 and 213 which are detachably secured to stationary support 214 and movable support 215, respectively. Inner plate-like members 211 and 213 are contoured on their inner faces to correspond to and to cooperatively nestle against and to lie in full abutment with the entire rear surface of the shell mold halves 217, 219 defining cavity 282. For the purpose of supporting the shell mold and attaching the same to the stationary inner plate-like member 211 when movable inner plate-like member is separated therefrom, there is provided on the outer or rear surface of shell mold half 217, a pair of outwardly projecting bosses 221, 223 which are received by corresponding apertures in the front face of inner plate-like member 211. Mold half 219 is suitably grooved to mate with mold half 217 so that they from a unitary mold when assembled and positioned in contact with the inner face of the member 211. Because of the direct contact between the rear surfaces of the mold halves 217, 219 and the abutting inner plate-like members 211, 213, respectively, a greater proportion of heat from the molten metal being cast in the shell mold is transmitted to the members 211, 213 than in the above described pin types of supporting assemblies. In order to enable the 30 continuous quantity production of large objects and to concurrently maintain a high quality in the cast article, it is desirable to provide supplementary means for cooling the plate-like members 211, 213. A suitable construction and means for accomplishing this objective will now be described in detail.

40 The supports 214 and 215 which are substantially similar are provided with substantially flat faces for cooperation with the corresponding inner plate-like members 211, 213. Each support is similarly provided with a relatively large approximately rectangular opening 224, as 45 may be seen in Fig. 7. Each support is provided with a hollow chamber 225 formed along each side thereof which chambers are connected at their lower ends by a hollow cross-chamber 227. Each side chamber 225 is provided with a vertically elongated opening 229 extending through the flat face thereof. A metallic plate 231 is interfitted between the flat face of each support 214, 215 and the cooperating inner plate-like members 211, 213, respectively. Plates 231 are provided with a pair of vertically elongated openings 233 therein, corresponding 50 and registering with each of the corresponding openings 229, and each plate 231 is provided with a vertically elongated central opening 235 which as illustrated in Fig. 7 is generally triangular in shape.

55 The back of inner plate-like members 211, 213 is hollow and except at the marginal edges is spaced from its cooperating plate 231 so as to form a passageway 237 between each opening 235 and the side openings 233 in each plate 231. From the construction as above described, it will 60 be apparent that there is continuous path of communica-

tion through the openings 235 in the plates 231, passageway 237, side apertures 233 in plates 231, cooperating openings 229 in supports 211, 213 and the cross passages 227 in each fixture 210, 212. Air or other cooling medium may be forced under pressure through cross passage 227 and out of central opening 235 or may be drawn in the opposite direction through the supports and inner plates by subatmospheric pressure. For the purpose of this invention, it is preferred that the air for cooling the inner plate-like members 211, 213 be drawn through the various passages therefor by suction. When suction is employed, the suction may be transmitted from each cross passage 227 to its cooperating side chambers 225 through the cooperating openings 229 in each of the supports and the cooperating openings 233 in the corresponding plates 231 to the space 237 between the corresponding plate-like members 211 or 213 and its support 214 or 215 respectively. The suction thus created within these spaces will cause air to be drawn through the central aperture 235 in each of the plates 231, through the various passages described and into the cross passages 227 from which it will be discharged. The air thus flowing through the central passages 235 in the plates 231 will extract heat from the members 211, 213 by flowing over the rear faces thereof. The rate of heat extracted from the members 211, 213 is preferably accelerated by providing a multitude of pins or vertically disposed fins 239 on the rear faces of the members 211, 213 and projecting into the path of flow of air over these rear faces.

The air drawn through the assembly shown in Fig. 8 is vented through the flue or stack 53 and the interconnecting channels between the assembly and the stack will now be described. In the stationary portion 210 of the assembly, the support 214 is provided with a passageway 241 as shown in Fig. 1 which is formed integrally with the cord 27 in communication with the cross passage 227 and extends through and opens the joint 243 between it and the adjacent cord 27. Joint 243 is constructed to receive hollow arm 25 and is internally provided with a communicating passage between the passageway 241 and the interior of arm 25. As mentioned hereinabove, the interior of arm 25 is in open communication with the interior of the central drum member 19 of the turret which in turn communicates with the upstanding flue 53.

The air drawn through the movable fixture 212 and over the rear surfaces of inner plate-like member 213 is conducted to the interior of central drum member 19 by means of a tube 247 which extends radially inwardly from the cross passage 227 with which it is in open communication. The inner end of tube 247 projects relatively loosely through an opening 249 provided therefor at the inner end of the cooperating arm 25 and in the periphery of the drum member 19, thereby connecting at all times the cross passage 227 of each movable fixture with the hollow interior of the drum 19. A suitable source of suction may be provided in connection with flue 53 and the suction device may be operated constantly or intermittently during the operation of the turret as desired. As will be noted in connection with Fig. 3, inner plate-like members 79, 81 are similarly provided with corresponding interconnecting air passages and suction may be employed, if desired, with any of the shell mold supporting assemblies of this invention by the use of the means illustrated or other suitable means which will be apparent to those skilled in the art. Cooling of the inner plate-like members is not necessary for continuous production however, especially where the shell mold is supported and maintained by pins such as in Fig. 9, wherein inner plate-like members 146 and 147 and cooperating plates 156, 158 are illustrated without communicating air passages.

In conventional permanent mold casting, the cast article sometimes tenaciously adheres to the surface of the permanent mold, and its removal from the mold face requires the application of considerable force which is customarily applied by hammering or the like. As previously sug-

gested with the use of shell molds, sticking of the cast article to the shell mold or to the shell mold supporting fixtures is substantially eliminated and the dislodgement of the cast article from the shell mold supporting fixture is relatively easy. The substantial lack of sticking is due primarily to the shell mold layer which is interposed between and separates the casting and the supporting fixtures.

One illustrative means suitable for dislodging castings from the shell mold supporting fixtures is shown in Figures 10 and 11. The shell mold supporting assembly there shown is of the same general type shown in Fig. 8 and previously described in connection with the molding of heavy articles, and is comprised of a stationary fixture 251 and a movable fixture 253. Each fixture is provided 15 with an inner supporting member 255 which is separated from the inner smooth abutting face of supports 257 by a centrally apertured plate 259. The rear surfaces of inner members 255 are recessed at 261 and provided with a plurality of cooling fins 263 and pins 264. Each fixture 20 is provided with an air cylinder 262 of conventional design having an inwardly projecting piston rod 265 extending through the central apertures 267 of plates 259. Rigidly attached to the inner end of piston rod 265 is a rigidly disposed rod or plate member 269 having a pair of inwardly projecting knockout pins 271 rigidly secured to its end extremities as by welding or the like. The inner ends 273 of knockout pins 271 are enlarged to present a greater surface area in abutment with the rear surface of each shell mold half 275. Means such as 30 springs 281 for returning knockout pins 271 to their "at rest" position, as shown in Fig. 10 when piston rod 265 is in its retracted position are interposed between the rear surface 277 of inner plate members 255 and the forward surface 279 of horizontally disposed rod 269. It will be appreciated by those skilled in the art that the number and location of knockout pins 271 will necessarily vary with the shape and size of the article being cast. Air cylinders 263 are supported by suitable bracket members (not shown) positioned beneath the air cylinders and 35 extending upwardly from cords 27 in the case of the stationary fixture 251 and from supporting bracket 140 in the case of movable fixture 253. The method of operation of air cylinders 263 and the automatic control thereof will be described hereinafter.

45 As previously mentioned the movable fixture 92 (Fig. 3) is maintained in cooperating relationship with respect to the stationary fixture 90 during that phase of rotation of the turret during which the molten metal is cast into the mold cavity 82, and until a sufficient time has 50 elapsed to insure the molten metal having solidified to such an extent as to make it feasible to open the mold and discharge the part thus cast from between them. The means for effecting this movement is best seen in Figs. 1 and 2. As there shown, a bracket member 310 extends 55 between and is supported on the upper surfaces of each adjacent pair of arms 25 adjacent the central drum 19 and each bracket 310 is provided with an upstanding flange 312 to the rear face of which the forward end of an air cylinder 314 is rigidly secured. The air cylinders 60 314 are of a conventional type including a piston rod 316 which projects outwardly therefrom through the outer end of the cylinder 314 and flange 312. The cylinders 314 are arranged so that the axis of each piston rod 316 extends centrally with respect to the radial center 65 line of its corresponding assembly.

The movable fixture 92 of each shell mold supporting assembly has fixed to its inward face as by means of screws 318, a yoke 320 which is provided with a central bore 322 arranged radially with respect to the axis of the rotation of the turrets and in axially aligned relation with respect to the corresponding piston rod 316. The outer end of each piston rod 316 is provided with a peripheral flange 324 adapted to abut against the rear face of the corresponding yoke 320, and a projecting end portion 70 75 326 which projects through the corresponding bore 322

in loosely received relation. The outer end portion of the end 326 is secured in place by means of a nut 328 threaded upon the outer end 326. An appreciable amount of free play laterally in the bore 322 insures that the entire weight of the movable fixture 92 is carried on the rails 99 without binding of the piston rod 316 in its cylinder.

For the purpose of actuating air cylinders 314, as well as air cylinders 263 (Fig. 10), a conventional valve structure is provided for each cylinder 314 and when present, the associated cylinders 263. The control valve structure indicated generally at 330 is mounted in adjacent relationship to the corresponding cylinder 314 upon the exterior surface of the central housing member 31. Each valve structure 330 is connected by means of a pipeline 332 with the forward end of the corresponding cylinder 314 and connected by a pipeline 336 with the rear end of its corresponding cylinder 314. Pipeline 332 is provided with a T 334 which is adapted to connect to each of pipelines 338 and 339 carried by the inward end of air cylinder 263 attached to the movable fixture 253 and the forward end of air cylinder 263 carried by stationary fixture 251, respectively. Pipeline 336 is provided with a T 340 which is adapted to connect to pipelines 342 and 344 attached to the forward end of air cylinder 263 carried by movable fixture 253 and the inward end of air cylinder 263 carried by stationary fixture 251, respectively. Each valve 330 is also provided with an air exhaust line or pipe 346 which as shown in Fig. 2 discharges into the interior of the drum 19. The valves 330 are interiorly in communication with the annular duct 33 in the member 31 so as to receive a supply of compressed air therefrom. Each valve 330 is provided with an operating arm 348, the outer end of which supports a roller 350 as best shown in Fig. 2. It will be understood that when the arm 348 is at one limit of its movable position, compressed air from the duct 33 will be admitted to one end of cylinders 314 while air will be permitted to escape from the opposite end thereof through the pipe 346 and when the arm 348 is at the opposite limit of its movable position, the reverse of these conditions will prevail. It will be understood that when air is admitted to one end of cylinder 314, that air is concurrently admitted to one end of each of the air cylinders 263 and when the arm 348 is at the opposite limit of its movable position, air will be admitted to the other end of each of the cylinders 263. It will be noted that when air is admitted through pipelines 336 to the inward end of cylinders 314 and piston rod 316 is extended radially outwardly closing fixtures 90 and 92, that air will be admitted to the ends of air cylinders 263 adjacent the shell molds so that piston rods 265 will be in their fully retracted position and ejector pins 271 will not extend beyond the inner surface 287 of the inner plate-like members 255. Similarly, it will be noted that when compressed air from the duct 33 is admitted to the forward end of air cylinder 314 and the movable fixture 92 is separated from stationary fixture 90, that air is concurrently admitted into the rearward ends of the air cylinders 263 so that piston rods 265 are simultaneously advanced inwardly relative to the shell mold and the ejector pins 271 are moved through each of the inner plate-like members 255 to thereby eject shell mold halves 275 and/or the solidified casting therefrom.

In order to effect an automatic actuation of the movable shell mold supporting fixtures in properly timed relation to the rotatable position of the turret, the following illustrative mechanism is provided. The stationary ring 51 which supports the stack 53 at the center of the turret is provided in its exterior surface with an annular T-slot 347 therein. Secured to the outer face of the ring 51 by means of bolts 349, the heads of which are received with the T-slots 347, is a pair of brackets 351 projecting radially outwardly from the ring 51. Each of the brackets 351 has secured to its lower face a cam

member 353. The cam members 353 are secured to the brackets 351 by means of a pair of bolts 355 extending through a radial slot 357 in the corresponding bracket 351, the construction thus permitting the cam members 353 to be adjusted radially of their corresponding bracket 351. The cam members 353 as best shown in Fig. 1 have a V-shaped face or operating surface 359 for engagement with the rollers 350 on the operating arms 348 of the various valves 330. One of the cam members 353 is arranged so that its V surface 359 converges in a radially outwardly direction so that upon engagement with the roller 350 of any valve arm 348, the valve arm will be caused to move to the outer limit of its movable position, and the other cam member 353 is arranged with its V surfaces 359 converging in an inwardly direction so that when it engages the rollers 350 of the valve arms 348, these arms will be caused to move to the inward limit of their movable position. By this means, as the turret revolves and the various rollers 350 successively engage first one of the cam members 353 and then the other cam 353, the valves will be operated first to effect a closing of the shell mold supporting fixtures and to retract piston rods 265, and then will be operated to separate the shell mold supporting fixtures and to simultaneously advance piston rods 265 to automatically eject the solidified casting and shell mold. The particular point at which the shell mold supporting fixtures are opened or closed may be readily varied by simply shifting the brackets 351 circumferentially over the ring 51 in the T-slots 347. It will be appreciated that the particular valve structure and control means for actuating the motion of piston rods 316 and 265 is illustrative only and may be varied by those skilled in the art without departing from the spirit of the invention.

From the foregoing, it will be apparent that there is provided an improved casting machine which is provided with means for supporting and maintaining in position during casting, expendable shell molds as well as means for automatically ejecting solidified castings from the shell mold supporting fixtures. It will furthermore be appreciated by those skilled in the art that there is provided a quantity production machine capable of producing castings which are characterized by the substantial absence of surface roughness and scale, and which require no annealing prior to working of the casting because the shell mold eliminates the contact between the molten metal and a chilled metal surface.

Various modifications and formal changes may be made in the specific embodiments of the invention herein described without departing from the substance of the broad invention.

What is claimed is:

1. A casting machine having a shell mold supporting assembly including in combination a pair of opposed fixtures, one of said pair of fixtures being stationary and the other of said pair cooperating with and movable toward and from the said stationary fixture, each said fixture comprising an outer support and an inner plate-like member detachably secured thereto, the front faces 65 of said inner plate-like members being contoured to conform to the rear surface configuration of a shell mold, and the front face of the inner plate-like member attached to said stationary fixture having apertures therein which serve to support a shell mold positioned between said inner plate-like members, and a shell mold positioned between said inner plate-like members.

2. A casting machine having a shell mold supporting assembly including in combination a pair of opposed fixtures, one of said pair being stationary and the other of said pair cooperating with and movable toward and from said stationary fixture, means for automatically advancing and retracting the movable fixture toward and from its cooperating fixture, each said fixture comprising an outer support and an inner plate-like

member detachably secured thereto, means carried by said inner plate-like member of said stationary fixture for supporting a shell mold, the front faces of said inner plate-like members being contoured to conform to the rear surface configuration of a shell mold, and the front face of the inner plate-like member attached to said stationary fixture having apertures therein which serve to support a shell mold positioned between said inner plate-like members, a shell mold positioned between said inner plate-like members, and means for cooling said inner plate-like members.

3. A casting machine for casting molten metal having a circular supporting turret, means for rotating the same, a plurality of uniformly spaced shell mold supporting assemblies adjacent the periphery of the turret and rotatable therewith, each assembly including in combination a pair of shell mold supporting fixtures, one fixture of each pair being stationary and the other fixture being movable toward and from its cooperating stationary fixture, means for automatically advancing and retracting each movable fixture toward and from its cooperating fixture, each said fixture comprising an outer support and an inner plate-like member detachably secured thereto, means carried by the inner plate-like member of each stationary fixture for supporting a shell mold, the front faces of said inner plate-like members being contoured to conform to the rear surface configuration of a shell mold, and the front face of the inner plate-like member attached to each stationary fixture having apertures therein which serve to support a shell mold positioned between said inner plate-like members, a shell mold positioned between said inner plate-like members, and means for cooling said inner plate-like members.

4. A casting machine having a shell mold supporting assembly including in combination a pair of opposed fixtures, one of said pair of fixtures being stationary and the other of said pair cooperating with and movable toward and from said stationary fixture, means for auto-

matically advancing and retracting the movable fixture toward and from its cooperating fixture, each said fixture comprising an outer support and an inner plate-like member detachably secured thereto, means carried by said inner plate-like member of said stationary fixture for supporting a shell mold, the front faces of said inner plate-like members being contoured to conform to the rear surface configuration of a shell mold, and the front face of the inner plate-like member attached to said stationary fixture having apertures therein which serve to support a shell mold positioned between said inner plate-like members, a shell mold positioned between said inner plate-like members, means for cooling said inner plate-like members, and means for automatically ejecting a casting from said fixtures, said ejecting means consisting of yieldable pin means mounted on the opposing faces of said stationary and movable fixtures.
